UNITED STATES PATENT OFFICE.

ALBERT B. MILLER AND WALTER H. KELLNER, OF GREEN BAY, WISCONSIN.

GAS HEATER.

Application filed April 14, 1926. Serial No. 102,014.

This invention appertains generally to new and useful improvements in heating appliances and has more specific reference to a novel and simplified gas heater.

5 The primary object of the present invention is to provide such a gas heater adapted primarily for use in the heating of houses and the like and which is to be positioned beneath the floor of the room of the house 10 or the like in which it is installed.

Another object of the present invention is the provision of such a gas heater provided with a maximum heat radiating surface.

Another object of the present invention is 15 to provide such a gas heater having associated therewith a new and novel type of burner together with improved means for lighting the same.

A further object of the present invention 20 is the provision of such a gas heater including a casing and a plurality of heat radiating baffle plates together with novel means for supporting the said plates whereby they may be moved exteriorly of the casing when 25 it is desired to light the burner.

A still further object of the present invention is to provide such a gas heater which while simple and compact in construction is nevertheless strong, sturdy and durable; 30 one which is cheap to manufacture and can be placed on the market at a reasonable figure, and one which will accomplish all of the objects and perform all of the functions claimed.

35 With these and numerous other objects in view, the invention resides in the novel construction, combination and arrangement of parts as will be more fully hereinafter described, illustrated in the accompanying 40 drawings and particularly pointed out in the appended claims.

In the drawings forming a part of this application and wherein like characters of reference denote corresponding parts 45 throughout the several views:

Figure 1 is a side elevation of a gas heater constructed in accordance with the present invention showing the cover in raised position.

50 Figure 2 is a top plan view of the burner.

Figure 3 is a sectional view taken on line 3-3 of Figure 2.

Figure 4 is a vertical central sectional view taken through the improved heater.

55 Figure 5 is a top plan view thereof partially broken away.

Reference now being had more particularly to the accompanying drawings wherein for the purpose of illustration has been disclosed a preferred embodiment of the present 60 invention, it will be noted that the same embodies in its construction a casing 10 which may be of any desired shape and size and which has been shown in the drawings as of substantially square formation. This casing 65 10 is adapted to be positioned beneath the floor of the room of the house or the like which is to be heated and is preferably supported in position by means of the right angularly directed flanges 11 formed on the 70 upper edges of the side and end walls of the casing.

Leading into the casing 10 immediately adjacent the bottom wall 12 thereof is an air pipe 13 which is secured at its inner end 75 to the angular coupling 14, which coupling is in turn secured to the lower end of the centrally disposed depending nipple 15 of the burner generally designated by the reference numeral 16 and comprising in its construction a bottom wall 17, the annular side wall 18 and the top wall 19. The central portion of the top wall 19 is depressed as at 20 and this centrally depressed portion is provided with a plurality of openings 21 which act to 80 separate and spread the gas flame.

Also leading into the casing 10 adjacent to and above the air pipe 13 is the main gas pipe 22 leading from a suitable source of supply and having its inner end secured to 90 the horizontal leg 23 of the burner nozzle 24 carried by the depending nipple 15 and provided with the restricted terminal opening 25. Positioned within the length of the main gas pipe 22 is a vertically disposed auxiliary 95 gas pipe 26 and disposed in the main gas pipe 22 at opposite sides of the auxiliary gas pipe 26 is the main valve 27 and the safety valve 28. The upper end of the auxiliary gas pipe 26 is directed laterally towards the 100 burner 16 and carries the nozzle 28 in front of which is disposed a fire starting fuse 29, said fuse being suspended from the bracket arm 30 swingably associated as at 31 with the nozzle 28. Disposed within the auxiliary 105 gas pipe 26 is a valve 32.

The fire starting fuse 29 is of any conventional or preferred construction and is of that type which will be lighted by the heat of the gas. That is to say, when the valve 110 32 is opened and gas is permitted to flow through the nozzle 28, the said gas contact-

ing with the fuse 29 will cause the same to burst into flame and this flame will, in turn, light the gas flowing from the nozzle 28. The lighted gas from the nozzle 28 will then 5 light the burner 16 as will more fully hereinafter appear. Thus, it will be seen that there is provided an automatic means for lighting the burner 16 so that the use of matches and the like is eliminated.

10 The upper edge of one of the side or end walls of the casing 10 is provided with the spaced rolled hinge sections 33 adapted to receive therebetween the complementary hinge sections 34 formed on one edge of the cover 15 35, a suitable pivot pin 36 extending through the aligned hinge sections 33 and 34 whereby to provide a hinged connection between the cover 35 and the casing 10. It will be noted that the greater portion of the cover 35 is 20 apertured to provide the openings 37 so as to permit the heat from the device to be thrown exteriorly thereof into the room where the heater is installed.

Carried by the bottom surface of the cover 25 35 is the depending inverted frusto-conical wall 38 which encircles the burner 16, the said wall 38 being bent inwardly and angularly as at 39 to provide a recess for the reception of the fire starting fuse 29 and the bracket arm 30. Also carried by the bottom surface of the cover 35 is the depending inner annular wall 40 spaced from the wall 38 and provided at its lower end with the angularly directed flange 41 encircling the 30 burner 16 and spaced slightly therefrom.

There is further secured to the bottom of the cover 35 centrally thereof, the downwardly and outwardly radiating arms 42, 43, 44 and 45, the lower ends of the arms 42 and 40 43 being secured as at 46 to the annular flange 41 of the wall 40. The arms 44 and 45 extend at right angles to the arms 42 and 43 and are suitably secured at their outer ends to the annular wall 40 intermediate 45 the upper and lower ends thereof. Secured to the arms 42 and 43 are the plurality of annular brackets 47 to which are suitably attached the upwardly and outwardly directed annular heat radiating baffle plates 48. Annular brackets 49 similar to the brackets 47 are secured to the arms 44 and 45 and carry the heat radiating baffle plates 50 similar to the baffle plates 48.

From the foregoing description, it will be 55 readily appreciated that when the cover 35 is raised, the annular walls 38 and 40 together with the heat radiating baffle plates 48 and 50 will be swung exteriorly of the casing 10 as shown in Figure 1 so that the lighting of the burner 16 may be readily accomplished. A suitable handle 53 is provided to facilitate the raising and lowering of the cover 35 and for the purpose of retaining the cover in a raised position when it is 60 desired to light the burner 16, there is pro-

vided a bracket arm 51 pivotally secured at one end to the said cover and provided adjacent its opposite end with a suitable notch adapted to engage the pin 52 carried by the casing 10.

When it is desired to light the present improved heater, the cover 35 is first raised to the position shown in Figure 1. The valve 32 is then opened and the gas flowing through the nozzle 28 will cause the fuse 29 to burst into a flame, as has been stated above, and this flame will then light the gas issuing from the said nozzle 28. The nozzle 28 is of such a type that the lighted gas therefrom will be forced over and above the burner 16 so that upon the opening of the valve 27, the gas will issue from the burner through the restricted opening 25 and the gas flame from the nozzle 28 will act to light the burner 16. The valve 32 is then closed and the cover 35 is also subsequently closed. The gas issuing from the burner 16 will heat the baffle plates 48 and 50 and the heat from these baffle plates will then be subsequently thrown through the apertured cover 35 into the room in which the appliance is installed. In order to turn off the burner, it is only necessary to raise the cover 35 and close the valve 27. The requisite amount of air to be mixed with the gas is permitted to enter through the air pipe 13 and air will also enter the casing through the cover 35 and the space between the walls 38 and 40.

From the foregoing, it will be seen that there has been provided a novel and simplified gas heater which is well designed for the purposes for which it is intended and it is to be understood that changes in the details of construction thereof may be resorted to without departing from or sacrificing the spirit of the invention so long as such changes fall within the scope of the appended claims.

What is claimed is:

1. A heater of the character described, comprising a casing having integral bottom and side walls, an apertured cover resting upon the top edges of said side walls and covering said casing, a heater element within the lower portion of said casing, and an inverted substantially frusto-conical body secured to the under side of said cover and extending into said casing to and surrounding said heater at its inner end.

2. A heater device of the character described, a casing body comprising integrally connected bottom and side walls, a cover for said casing body, having heat escape apertures formed therethrough, a pair of downwardly extending diverging arms secured to the central under side of said cover, a burner structure within the lower portion of said casing and having said arms lying thereover, and a plurality

of concentrically arranged annular heat deflecters surrounding said arms and arranged in spaced relation from the lower to the upper portion thereof, said deflecting elements being of gradually decreasing diameter from the lower to the uppermost ones thereof.

3. A heater device of the character described, a casing body comprising integrally connected bottom and side walls, a cover for said casing body, having heat escape apertures formed therethrough, a pair of downwardly extending diverging arms secured to the central under side of said cover, a burner structure within the lower portion of said casing and having said arms lying thereover, and a plurality of concentrically arranged annular heat deflecters surrounding said arms and arranged in spaced relation from the lower to the upper portions thereof, said deflecting elements being of gradually decreasing diameter from the lower to the uppermost ones thereof, and an inverted frusto-conical body secured to the under side of said cover and surrounding said heat deflector elements, the lower portion of said body extending through and surrounding said burner.

4. A heater device of the character described, comprising a casing body, a burner structure within the lower portion of said body, an inverted substantially frusto-conical body extending inwardly from the under side of said cover and surrounding said burner from its inner end, a depend-

ing annular wall extending from the under side of said cover and spaced from said body, an annular flange formed about the lower edge of said wall and encircling said burner, and a plurality of annular heat deflector elements arranged in spaced relation and cone formation above said burner.

5. A heater device of the character described, comprising a casing having an apertured cover hingedly secured thereto, a burner within the lower portion of said casing, an inverted frusto-conical body secured to the under side of said cover and depending into said casing and surrounding burner at its inner end, a depending annular wall secured to the under side of said cover and spaced from said body, an annular flange formed about the inner end of said wall and encircling said burner, a pair of arm members secured to the central under side of said cover and extending downwardly in divergent relation, and having their lower ends secured at diametrically opposite points to said flange, and a plurality of annular heat deflecting members encircling said arms, and arranged in spaced relation from the upper to the lower ends thereof, said heat deflecting elements being of gradually decreasing diameter from the lower to the uppermost ones thereof.

In testimony whereof we affix our signatures.

ALBERT B. MILLER.

WALTER H. KELLNER.
